(57) CLAIM

I claim the ornamental design for a pencil holder, as shown and described.

DESCRIPTION

FIG. 1 is a top front perspective view of a pencil holder showing my new design, the pencil depicted by means of broken lines being shown for illustrative purposes only and forming no part of the claimed design;

FIG. 2 is a top plan view thereof;

FIG. 3 is a left side view thereof;

FIG. 4 is a front view thereof;

FIG. 5 is a right side view thereof;

FIG. 6 is a bottom view thereof; and,

FIG. 7 is a rear view thereof.
